US0D1107103S

(12) **United States Design Patent** (10) **Patent No.:** **US D1,107,103 S**
(45) **Date of Patent:** **** Dec. 23, 2025**

(54) **CAMERA LENS COVER**

(71) Applicant: **GoPro, Inc.**, San Mateo, CA (US)

(72) Inventors: **Bessy Wen-Han Liang**, San Jose, CA (US); **Huy Phuong Nguyen**, Alpine, UT (US)

(73) Assignee: **GoPro, Inc.**, San Mateo, CA (US)

(**) Term: **15 Years**

(21) Appl. No.: **29/935,794**

(22) Filed: **Apr. 3, 2024**

(51) LOC (15) Cl. **16-05**

(52) U.S. Cl.

USPC **D16/219**

(58) **Field of Classification Search**

USPC D9/435, 455; D16/130, 134, 136, 200, D16/219, 237; 396/419, 535

CPC G02B 23/16; G03B 11/041; G03B 11/043

(57) **CLAIM**

The ornamental design for a camera lens cover as shown and described.

DESCRIPTION

FIG. 1 is a front, right, top perspective view of a camera lens cover of our new design;

FIG. 2 is a rear, left, bottom perspective view thereof;

FIG. 3 is a front view thereof;

FIG. 4 is a rear view thereof;

FIG. 5 is a right view thereof;

FIG. 6 is a left view thereof;

FIG. 7 is a top view thereof; and,

FIG. 8 is a bottom view thereof.

1 Claim, 7 Drawing Sheets
